United States Patent Office.

E. A. MÜLLER AND THEODOR STOCK, OF CHICAGO, ILLINOIS.

Letters Patent No. 78,118, dated May 19, 1868.

IMPROVED DOUBLER FOR STILLS.

The Schedule referred to in these Letters Patent and making part of the same.

TO ALL WHOM IT MAY CONCERN:

Be it known that we, E. A. MÜLLER and THEODOR STOCK, of Chicago, in the county of Cook, and State of Illinois, have invented a new and improved Doubler for Stills; and we do hereby declare that the following is a full, clear, and exact description thereof, which will enable others skilled in the art to make and use the same, reference being had to the accompanying drawing, forming part of this specification.

The drawing represents a vertical central section of our improved doubler.

This invention relates to a new apparatus for rectifying spirits on their passage from the still to the cooling-worm.

The object of the invention is to so construct a rectifier or doubler that the process of distillation may be quickly carried on, that directly from the mash pure spirits may be produced, and that the different grades of liquor may be well separated from each other.

The invention consists in the use of an upright cylinder, closed at both ends, and provided within its interior with a series of pans and abutting plates, by means of which the ascending vapors will be detained, and the products of condensation arrested, so that the lower degrees of spirits will be separated from the finer, while the pure alcoholic vapors are allowed to escape to the cooler, and the low-wines reconducted to the mash.

The invention also consists in arranging, around the outside of the cylinder, annular cooling-vessels, which communicate with each other and with the dish-shaped cover of the cylinder, by means of pipes, so that cooling-liquid, poured upon the cover, will gradually find its way to the lower annular pan, so as to have passed along the entire height of the cylinder.

A, in the drawing, represents an upright sheet-metal or other cylinder, constructed of one piece, or of two or more. In the latter case the various sections are firmly united, so that one complete air and water-tight cylinder is produced.

The cylinder is provided with a bottom-plate, B, and if desired, with a removable covering-plate, C, the latter being set below the upper edge of the cylinder, so as to form a dish, as shown. The covering-plate C is somewhat higher in the centre than at the edges, so that any liquid poured upon it may flow towards the edges, whence it is conducted to the outside through a pipe, a.

Around the outside of the cylinder is arranged a series of annular pans or vessels, D D, into the uppermost of which the liquid flowing from the cover C is conducted. The vessels D D communicate with each other by means of pipes b b, as shown. The lowermost vessel, D, has a pipe, c, through which its contents may be carried off to a suitable receptacle.

The cooling-liquid, for producing the condensation of the low-wines, is poured upon the plate C, and then gradually flows down from vessel to vessel D. As the vessels D are so arranged that their inner walls are formed by the outside of the cylinder A, the walls of the cylinder will be cooled by the liquid in the vessels.

The vapors are conducted from the still to the bottom or lower part of the cylinder A, in a pipe, d, and another pipe, e, entering the lower part of the cylinder, serves to carry off the low-wines.

Within the cylinder A is arranged a series of dishes, E E, perforated plates F F, and combined plates and dishes G. The dishes E are horizontal plates, with a depression in the centre for retaining liquid matter. The diameter of these dishes is smaller than that of the cylinder, as shown, so that a space is left between them to allow the vapors to pass upward. The dishes E are supported by brackets or legs f f, as indicated. The plates F fit close within the cylinder A, and are perforated in the middle, so that the vapors can pass upwards through them.

The combined plate and dish G is a small dish, g, suspended, by means of pins h h, from a plate, i, the latter being perforated in the middle, and fitted close within the cylinder, as shown.

The vapors, which enter the cylinder A, through the pipe d, strike against the lower sides of the dishes E and plates F, and are detained thereby sufficiently long to allow the condensation of the impure parts. The low-wines drop from the lower dish E and plate F upon the bottom, B, of the vessel A, and are carried back to

the still by the pipe *e*. Whatever drops off the under sides of the upper dishes *E* of plates *F* is caught in the dishes *E*, and retained therein. The vapors have to pass in a zigzag line around the dishes *E*, and through the plates *F*. Striking against the bottom of a plate, *i*, the impure vapors are condensed and drop into the dish *g*, while what condenses directly above the plate *i* is retained on the same, its central perforation being guarded by a short pipe, *j*, as shown. Those vapors which are not condensed in the apparatus escape from the upper part of the same through a pipe, *k*.

This apparatus may be made of suitable size, according to the size of the still, and to the quantity of liquor to be distilled. The number of plates and dishes *E F G* in its interior, and of vessels *D D* around its outside, can be varied at pleasure.

We claim as new, and desire to secure by Letters Patent—

1. Arranging around the outside of a rectifier or doubler, *A*, a series of annular cooling-vessels, *D D*, which communicate with the upper part of the vessel *A*, substantially as and for the purpose herein shown and described.

2. The arrangement and combination, within the cylinder *A*, of the dishes *E*, plates *F*, and combined dishes and plates *G*, all made and operating substantially as herein shown and described.

E. A. MÜLLER,
THEODOR STOCK.
